UNITED STATES PATENT OFFICE

EDWARD E. BARTLETT, OF SAPULPA, OKLAHOMA

DESIGN FOR A PITCHER OR SIMILAR ARTICLE

Application filed June 18, 1931. Serial No. 40,258. Term of patent 14 years.

To all whom it may concern:

Be it known that I, EDWARD E. BARTLETT, a citizen of the United States, residing at Sapulpa, Creek County, in the State of Oklahoma, have invented a new, original, and ornamental Design for Pitcher or Similar Article, of which the following is a specification, reference being had to the accompanying figure, forming a part thereof, and in which the figure is a side elevational view of the pitcher or similar article, showing my new design.

I claim:

The ornamental design for a pitcher or similar article, substantially as shown.

In witness whereof, I have hereunto set my hand.

EDWARD E. BARTLETT.
